JASPER BLACKBURN, OF WEBSTER GROVES, MISSOURI

WINDOW SCREEN

Application filed November 2, 1925. Serial No. 66,241.

My invention relates to improvements in window screens, and has for its primary object a window screen composed of two frames having a metal frame interposed therebetween, this metal frame effectually prevents 5 warping of the screen and also prevents it from becoming out of shape. This is a feature which frequently happens with window screens of the ordinary window frame construction since in the handling of them they 10 are liable to become twisted out of shape, that is the corners will no longer be square and their entire frame will assume a diamond shape. This not alone makes the screen hard to fit into windows but also stretches and 15 distorts the wire cloth so that it no longer presents a neat, tight appearance but is loose and bulges.

A further object is to construct a window screen which is re-inforced and which can be 20 readily taken apart for recovering with wire cloth in the event the same should become broken.

In the drawings:

25 Fig. 1 is a face view of my improved screen; Fig. 2 is an edge view of the same;

Fig. 3 is a face view showing one of the frames removed;

30 Fig. 4 is an inside face view of the removed frame showing the manner of attaching the wire cloth thereto;

Fig. 5 is an enlarged fragmental longitudinal section showing the manner of securing the various frames together;

35 Fig. 6 is an enlarged perspective view of one corner of the metal frame illustrating one manner of securing the same together; and

40 Fig. 7 is an enlarged fragmental view of one of the corners of the wooden frames showing one manner of securing them together.

In the construction of my device, I employ a pair of frames 7 and 8. These frames are 45 of identical size and are secured together at their corners by means of corrugated brads 9. This, however, is only one manner of securing the corners as they may be secured together by any means well known in the joinery art, that is either by dowels, mortise and 50 tenon or similar securing means. Between

these frames 7 and 8 is placed a metal frame composed of strips 10 and 11. These strips are preferably lapped at their ends and spot-welded as illustrated in Fig. 6 although, if desired and found more convenient, other 55 fastening means may be used.

The members 10 and 11 are provided with tapered openings 12 which receive the heads of the screws 13. These screws are for the purpose of securing the frame 8 to the metal frame. The metal frame is also provided with openings 14 which are located intermediate the openings 12. Concentric with the openings 14 are openings 15 which are formed through the frame 8 and which receive screws 16. These screws extend into the frame 7 and are for the purpose of securing it in position on the metallic frame. 60

The screen cloth 17 is secured to the frame 7 by means of tacks or similar fastening 70 means 18. The metallic frame is preferably wider than the wooden frames so as to leave a projecting edge or flange entirely around the frame as illustrated in Figs. 1 and 2. In this way the top and bottom edges or 75 flanges make a close joint between the window sill and the upper window while the side edges bear against the parting strips which are between the two windows or the vertical edges can be inserted in a grooved strip and act as slides so that the window can be moved upward and downward.

The window screen may also be fastened on to the window frame by means of hooks, 80 hinges or the like. In fact my structure lends 85 itself to any of the well known mountings for screen windows that are used at the present time. I may also, if desired, make the face of the metallic frame of the same width as the wooden frames without departing 90 from the spirit of my invention.

95 My device is assembled as follows: After the various frames have been made, the frames 7 and 8 being preferably of identical size, the metallic frame is assembled and secured at its corners so that its opening will be of the same size as the frames 7 and 8. The openings 12 and 14 are then formed in the metallic frame and the frame placed on the wooden frame 8 so that the openings of both 100

frames are in alignment. The screws 13 are then placed in position, thus firmly uniting the metallic frame to the frame 8. A drill is then placed in the openings 14 and the openings 15 drilled through the frame 8. The frame 7 is laid with its outer face down and the wire cloth 17 secured in position on the opposite face by means of the tacks 18. The frame 7 is then placed on the metallic frame with the wire cloth next to the frame and with its opening in alignment with the openings of the metallic frame and the frame 8. The frames are then held together and inverted so that the frame 8 is uppermost and the screws 16 placed in position. In this manner all three frames are firmly united and by reason of the metallic frame being located between the two wooden frames, all possibility of these frames becoming mis-
shapen, due to rough handling etc., is eliminated. Should the screen cloth become broken or need replacement, it is only necessary to remove the screws 16 after which the frame 7 can be lifted from its place, the old screen cloth removed, and new cloth put in its place after which the frame is again secured in position, as before described.

Having fully described my invention, what I claim is:—

- 30 1. A window screen comprising a rectangular metal frame having spaced apart openings formed therethrough intermediate its edges, certain of said openings being countersunk on one face of said frame, a wooden frame of less width located on one face of said metallic frame, fastening means extending through said countersunk openings of the metallic frame and into the wooden frame for securing the same together so that there will be no projections on the metallic frame, a second wooden frame of the same size as the first mentioned wooden frame, a screen cloth secured to said frame, and fastening means passing through said first mentioned wooden frame, the remaining openings in the metallic frame and into the last mentioned wooden frame so that said last mentioned wooden frame is secured to said metallic frame on the face opposite that to which the first mentioned wooden frame is secured thereby forming a double wooden frame having an intermediate outwardly extending metallic projection extending entirely around said frame.
- 45 2. A window screen comprising a rectangular metallic frame having spaced apart openings formed therethrough intermediate its edges, certain of said openings being countersunk on one face of said frame, a wooden frame of less width located on one face of said metallic frame so that said metallic frame will project beyond the outside edges thereof, fastening means extending through said countersunk openings in the metallic frame for securing said metallic frame and wooden frame together, a second wooden frame of the

same size as said first mentioned wooden frame located on the opposite side of said metallic frame, fastening means passing through said first mentioned wooden frame, the remaining openings in the metallic frame and into said last mentioned wooden frame so that when all of said frames are secured together, a double wooden frame with a metallic flange projecting outwardly intermediate said frames is formed and a sheet of screen cloth interposed between said last mentioned wooden frame and said metallic frame.

In testimony whereof I have affixed my signature.

JASPER BLACKBURN.
